ATTYS.

UNITED STATES PATENT OFFICE.

MANSFIELD M. WEST, OF CLEVELAND, OHIO, ASSIGNOR TO THE UNIVERSAL SHOE PLATE COMPANY, OF CLEVELAND, OHIO, A CORPORATION OF OHIO.

SHOE PLATE.

1,418,894.

Specification of Letters Patent. Patented June 6, 1922.

Application filed August 30, 1917. Serial No. 188,901.

To all whom it may concern:

Be it known that I, MANSFIELD M. WEST, a citizen of the United States, residing at Cleveland, in the county of Cuyahoga and 5 State of Ohio, have invented a certain new and useful Improvement in Shoe Plates, of which the following is a full, clear, and exact description, reference being had to the accompanying drawings.

10 This invention relates to improvements in that class of devices known as shoe plates, for protecting the soles and heels of boots and shoes from wear.

The invention pertains more particularly 15 to the sort of shoe plates that are formed of sheet metal, and the features which constitute my invention will be hereinafter specifically pointed out.

In order that these features may be better 20 understood and more fully appreciated, it may be well to recite what has heretofore been accomplished in this line. Shoe plates of the stamped metal variety are at present in great demand, and all with which I am 25 familiar, while being reasonably efficient, possess qualities and peculiarities which make them somewhat undesirable. For instance, heretofore stamped metal plates have had their prongs punched either from the 30 wearing area of the plate and turned downward, or turned downward from the periphery of the plate. In the former case the wearing property of the plate is obviously impaired, while the edge of the plate is not

35 held down sufficiently tightly against the surface of the shoe heel or sole to prevent objects, such as splinters, from catching beneath the plate resulting in its being jerked off. This is because the prongs are spaced

40 inward from the edge of the plate. In the second case, where the prongs are turned down from the edge of the plate, the connecting portions of the prongs and plate, being located at points of exposure to intense 45 wear, soon become worn away, with the result that the plate is separated from the prongs and is lost long before it has served its usefulness.

Furthermore, in all plates with which I 50 am familiar where the prongs are turned down from the edge of the plate, there are three prongs, one being set well in from the edge of the sole or heel while the two remaining prongs are in close proximity to the 55 edge (the region of greatest wear). Conse-

quently the outer prongs soon wear away and the plate turns upon the third prong, causing the prong to withdraw from the hole thus made larger, or the plate to break away from the prong.

It is the object of my invention to overcome these difficulties by providing a plate with at least four prongs; turning the prongs down so far as practicable within the area of the plate proper so as to be protected by the body portion of the plate; and by further very slightly turning the edge of the plate downward between the prongs so that such turned down edge portion will embed itself into the surface of the sole or 70 heel, thereby to produce a tight joint between the plate and such surface, insuring against splinters or other objects entering beneath the plate and jerking it off.

Further objects of my invention are to 75 provide a plate wherein the metal is properly distributed, so that the plate will stand, to facilitate driving; and to corrugate the plate lengthwise between the opposed end prongs so as to stiffen its body portion to 80 prevent its bending in driving, and also to prevent slipping, and enhance the wearing qualities of the plate.

A plate wherein the foregoing objects are attained is illustrated in the accompanying 85 drawing. Fig. 1 is a perspective view of the plate; Fig. 2 shows the plate, in plan view, applied to a heel; and Fig. 3 is a section on the line 3—3 of Fig. 2.

The plate is practically of universal adaptability, the outer edge of the plate being curved to fit the contour of the average sole or heel. The body portion 1 of the plate is shown as having its outer edge so curved, and its inner edge is preferably of substantially the same curvature, having practically the same radius, so that the plate is somewhat wider at its middle than at each end. Also, preferably, the ends of the plate converge inwardly on lines crossing each other 95 substantially midway between the centers on which the inner and outer edges are described. This design enhances the balancing of the plate. A prong 2 is turned down from each end of the plate and is inset somewhat 100 from the outwardly curved edge so as to remove it slightly from the region of greatest wear; and a similar prong 3 is turned down from each end of the inner curved edge of the plate. The prongs are preferably with- 105

110

in the regular outline of the plate, as indicated in Fig. 2. The ends and inner edge of the plate are shown as curved downward somewhat to embed themselves within the material of the sole or heel, as revealed in Fig. 3.

The body portion 1 of the plate is provided with lengthwise corrugations 4 which have the three-fold purpose of strengthening the plate against bending, of increasing its wearing qualities, and of preventing it from slipping.

In Fig. 2, I have shown a straight line *a—a* extending through the outer prongs 2 to enable one to see at a glance that there is more material to the inner side of the line (that is, the side towards the prongs 3) than there is on the outer side, thus indicating that the plate would readily stand and not overbalance toward the outer side. This is highly important in articles of this character for it enables them to stand without being held, preparatory to driving. I wish to explain, also, that the side and inner edge portions

of the plate are turned down so slightly that they do not prevent driving the plate absolutely flat against the surface of the sole or heel.

Having thus described my invention, what I claim is:—

A shoe plate constructed of sheet metal and comprising a body portion having a convexed outer edge and straight ends substantially normal thereto and an inner edge connecting said ends, a prong depending from each end and inset a comparatively short distance from the aforesaid outer edge whereby it is removed from the region of greatest wear, and a prong depending from each end of the inner edge; the material of the body portion by reason of the latter's shape being properly distributed with regard to the wear imposed thereon when the plate is in use and so as to cause the plate to stand alone preparatory to driving it.

In testimony whereof, I hereunto affix my signature.

MANSFIELD M. WEST.
